(57) **CLAIM**

We claim the ornamental design for a TV display screen with a transitional graphical user interface, as shown and described.

DESCRIPTION

The patent or application file contains at least one drawing executed in color. Copies of this patent or patent application publication with color drawing(s) will be provided by the office upon request and payment of the necessary fee.

FIG. 1 is a front-side view of a first image of the TV display screen with a transitional graphical user interface showing our new design;

FIG. 2 is a front-side view of a second image or the TV display screen with a transitional graphical user interface showing our new design; and,

FIG. 3 is a front-side view of a third image of the TV display screen with a transitional graphical user interface showing our new design.

The appearance of the transitional image sequentially transitions between the images shown in FIGS. 1-3. The process or period in which one image transitions to another image forms no part of the claimed design.

The characteristic point of the present design is that the color of the main menu affects the color of the sub-menu. If the color of the main menu is dark purple, the same color (purple) of the sub-menu becomes brighter.

The broken lines shown in the drawings illustrate portions of the TV display screen and GUI that form no part of the claimed design.

1 Claim, 2 Drawing Sheets
(2 of 2 Drawing Sheet(s) Filed in Color)
